Attorney.*

UNITED STATES PATENT OFFICE.

GREGORY J. COMSTOCK, OF PITTSBURGH, PENNSYLVANIA.

NAIL AND THE LIKE AND METHOD OF MAKING THE SAME.

Application filed September 29, 1927. Serial No. 222,753.

My invention relates to an improvement in nails and other fastening devices, such as cotter pins, bolts, screws, staples, and the like, and more particularly to the treatment or formation of such articles in a manner which will render them more difficult of removal from articles or other holding members with which they may be associated in co-operative relation.

Heretofore, various means have been employed for rendering nails, for instance, less liable to become accidentally withdrawn, some of such means being by applying a coating of cement, varnish, lacquer or shell-lac, for instance to the nails, so that they will have better frictional engagement with wood or other material into which they may be driven. These coatings tend to make the nails stick together when assembled in bulk and hamper the use thereof in nailing machines, besides being often unpleasant to handle when being manually held and driven. Spurs or indentations have also been made on the shank or body of the nail to cause them to be more firmly held in operative position, but such practice tends to weaken the nails and also renders them less suitable for handling.

Still another practice followed, in connection with upholsterers' nails and railroad spikes, has been that of splitting the nail somewhat at the point in such a manner that the split portions will spread when being driven, to thereby produce a clinching effect. While this method results in the nail being held more firmly, it may prevent removal thereof under any circumstances, and will at least result in excessive tearing or destroying of the material, into which they may be driven. This feature is particularly objectionable in the case of upholsterers' nails which must sometimes be removed in order to permit replacing of the upholstering material.

One object of my invention is to provide nails and other securing elements with surfaces or shanks of such form that they will resist separating movement to a marked degree, but wherein the nail or the like is not seriously weakened, and wherein no coating material is required.

Still another object of my invention is to simplify and improve generally the structure and form of holding devices, and the method of manufacturing the same.

Specifically stated, my invention contemplates the sand-blasting of nails, etc., or the stock from which the articles are to be made, so that the sand-blasted surfaces will increase the resistance to separation or withdrawal movement of the nails.

While I hereinafter refer more particularly to sand-blasting, it will be understood that the roughened surface may be produced in other ways, as by acid treatment, and that other abrasives than sand may be employed.

In the accompanying drawing, wherein I have indicated some of the ways in which my invention may be employed, Figure 1 represents a piece of wire or bar stock that has been sand-blasted previous to the formation of nails therefrom; Fig. 2 is a view showing a completed nail whose entire shank portion is sand-blasted; Fig. 3 shows a nail having the major portion of its shank or body sand-blasted, but with its point smooth; Fig. 4 shows a bolt made according to my invention, and Fig. 5 represents a wood screw similarly treated.

The sand-blasting or acid treatment may be effected in the case of the wire of Fig. 1, as it enters a nail-making machine (not shown) in which case the entire nail will be roughened, as shown in Fig. 2 but it will be understood that the nails may be formed of an ordinary smooth wire or bar and thereafter roughened by sand-blasting, etc.

In the case of the nail of Fig. 3, the point of the nail may be left smooth, either for the purpose of permitting it to be more readily started to its driven position, or such smooth point may be merely incidental to the fact that the nails are held at their points while being roughened. The heads could be similarly held, in which case the outer portion of the nail might be smooth, but this would not be objectionable since the holding effect of the nail is largely required at points a considerable distance away from the head of the nail.

Referring to Fig. 4, I show a bolt whose threaded portion is sand-blasted. This roughening of the thread may extend through substantially the entire length thereof or may extend only from the outer end of the nut when in its normal position to the extremity of the bolt. The sand-blasting has the effect of preventing loosening of the nut by reason of vibration. A lock nut could also be employed in conjunc-

tion with the holding nut, in which case the sand-blasting would still further contribute to prevent unscrewing of the nuts.

A wood screw treated according to my 5 invention would have somewhat the appearance shown in Fig. 5.

The invention is capable of use in connection with various other articles, including cotter pins, which if roughened and 10 driven into a snug-fitting hole would be more firmly retained in place.

The invention is also advantageous in connection with the formation of what are termed "furring nails" that carry a spacing 15 element which embraces the shank of the nail and is used for spacing plaster and cement reinforcement from studding, in that the roughened nail will hold the spacing element releasably positioned on the nail at a 20 desired point, thus making for convenience in assembling of the reinforcement and preventing the spacing element from sliding off previous to installation.

After the nails have been roughened, they 25 may be galvanized or not, as desired, since the galvanizing operation does not destroy the rough quality of the nail.

The sand-blasting results in a cutting away of the softer portions of the nail shank, 30 leaving the harder portions thereof remain in the nature of protuberances which engage the wood fibers that are of course held tightly against the shank of the nail by reason of the compressibility of the wood, 35 necessitating the tearing of the fibers upon withdrawal of the nail.

It has been found that roughening of nails, as above described, greatly increases their resistance to withdrawal, as compared to the unprocessed or common nail, and that 40 their resistance to removal is also much greater than in the case of coated nails, referred to above. In some cases, the nails will have a resistance to withdrawal which approaches the resistance offered by wood 45 screws of approximately the same size.

In the appended claims, it will be understood that the term "nail" is used in a broad sense to include cotter pins, etc., as defined above, and that sand-blasting is also used in 50 its broad sense to include various equivalent means of roughening.

I claim as my invention:—

1. A nail having at least a portion of its shank sandblasted, whereby a portion of the 55 nail is cut away by the sandblasting action to provide a roughened surface.

2. In the art of fastener making the step which comprises so sandblasting a surface upon a fastening means to be driven into 60 another article as to roughen said surface.

3. The method of making nails or the like, which consists in sandblasting the stock from which the articles are to be formed, in order to produce a roughened frictionally 65 resistant surface, and thereafter shaping the stock to the desired contour, while leaving the article in the aforementioned roughened condition.

In testimony whereof I, the said GREGORY 70 J. COMSTOCK, have hereunto set my hand.

GREGORY J. COMSTOCK.
